Attorney:

UNITED STATES PATENT OFFICE

ARMANDO GUTMANN, OF TURIN, ITALY

PRINTING CYLINDER FOR INTAGLIO PRINTING MACHINES

Application filed April 11, 1931. Serial No. 529,477.

My present invention relates to printing cylinders of intaglio printing machines and it has for its object an improved printing cylinder of this type intended to carry the impression or design plate or sheet.

More particularly my invention has for its object to provide means whereby the impression or design plate or sheet, usually made of copper or other metal, may be readily secured on the peripheral surface of the printing cylinder and placed under tension, said means being operable from one end of the printing cylinder.

According to my invention I provide a hollow cylinder, the opposite ends or heads of which are provided with hub members constituting at the same time the journals or bearing surfaces of the cylinder. Extending through said hub members is a shaft supported thereby.

Provided in the peripheral surface of the cylinder are two diametrically opposed gaps, one of which receives a fixed comb serving to guide and adjust a movable comb supported on three or more internal brackets made integral with the shaft, whilst the second gap serves to facilitate the mounting of the inner parts, said second gap being subsequently closed by means of an armature or block flush with the outer peripheral surface of the cylinder. Arranged at one end of the cylinder is an operating mechanism enabling the inner shaft to be rotated to a desired angle for moving the movable comb to the amount required for placing under tension and attach the impression or design sheet or plate onto the peripheral surface of the cylinder.

In order that the invention may be clearly understood and readily carried into effect, reference is made to the accompanying drawing, wherein:

Fig. 1 is a longitudinal section partly in elevation of my improved cylinder.

Fig. 2 is an elevation of same.

Figs. 3 and 4 are two cross sections of the cylinders with the closing or tensioning comb in two different positions.

Fig. 5 shows the comb operating mechanism.

The same reference numerals are used to indicate corresponding parts in the various views.

The main body of the cylinder 1 has at its opposite ends 2 hub members 3 forming bearing surfaces for the supporting journals 4 of said cylinder. The main body 1 is moreover provided with two longitudinal gaps 5, in one of which the fixed comb 6 and movable comb 7 are arranged, whilst the other gap is closed by means of an armature or block 8. The fixed and movable combs are provided with teeth 9 serving to guide and adjust the movable comb 7 in its movements. The movable comb 7 is supported on arms 10 fast on the shaft 11 held in the axis of the hub members 3. At one of the outer ends of the cylinder the hub member 3 carries a bracket 12 secured thereto for two opposite screw spindles 13, whereby the double link 14 fast on the shaft 11 may be moved in either direction.

By the rotation of the screw spindles 13 in either direction the shaft 11 will be rotated and said shaft in turn will displace the movable comb 7. With the movable comb in the position shown in Figure 4, there is provided a gap 15 between the fixed and movable combs, and the inturned ends of the impression sheet, which impression sheet encircles the cylinder, will be inserted into the gap 15, whereupon the operating mechanism is actuated to cause the movable comb 7 to move to the position shown in Fig. 3, whereby the impression or design sheet or plate will be secured to the cylinder and placed under tension.

Having now fully described my said invention, what I claim and desire to secure by Letters Patent, is:

1. A means for attaching and tensioning a design plate to the printing cylinder of a printing machine, comprising a movable comb, and inner shaft and means for operating said shaft for the purpose of displacing said movable comb, of hub members at the opposite ends of the cylinder forming supporting journals therefor and supporting said inner shaft, two longitudinal diametrically opposed gaps in the peripheral surface of the cylinder, one gap serving to facilitate

- the mounting of the inner parts, a fixed comb in the second gap arranged to guide and adjust said movable comb, suitable brackets on the inner shaft for supporting said movable comb, a double link on said shaft, and two screw spindles adapted to act on said double link for rotating the inner shaft and thereby displacing the movable comb, substantially as and for the purpose set forth.
- 10 2. A means for attaching and tensioning a design plate to the printing cylinder of a printing machine, comprising a movable comb, and inner shaft and means for operating said shaft for the purpose of displacing said movable comb, of hub members at the opposite ends of the cylinder forming supporting journals therefor and supporting said inner shaft, two longitudinal diametrically opposed gaps in the peripheral surface of the cylinder, one gap serving to facilitate the mounting of the inner parts, and a fixed comb in the second gap arranged to guide and adjust said movable comb.
- 15 3. A means for attaching and tensioning a design plate on a printing cylinder including a fixed comb arranged in the periphery of the cylinder, a movable comb guided by the fixed comb and serving in movement in one direction to engage and tension one end of the design plate, a member arranged axially of the printing cylinder, means carried by the member for operating the movable comb, and means beyond the ends of the cylinder for operating said member.
- 20 4. A means for attaching and tensioning a design plate on a printing cylinder including a fixed comb arranged in the periphery of the cylinder, a movable comb guided by the fixed comb and serving in movement in one direction to engage and tension one end of the design plate, a shaft extending axially of the cylinder and providing a support for the cylinder, elements carried by the shaft and connected to the movable comb for operating the latter, and means cooperating with the shaft beyond one end of the cylinder for operating the shaft to control the movable comb.

ARMANDO GUTMANN.
